OIL BURNER

John Alger Dahlstrom, Bay Village, and William A. Bryson, Lakewood, Ohio, assignors to Perfection Stove Company, Cleveland, Ohio, a corporation of Ohio

Application October 5, 1933, Serial No. 692,306

17 Claims. (Cl. 158—92)

This invention relates to improvements in that class of combustion apparatus in which there is a burner bowl equipped with means for delivering fuel thereto and having a relatively large opening in its wall through which access is had to its interior for lighting and cleaning purposes.

The invention has to do more particularly with means for admitting air to the burner bowl for promoting combustion, and it is especially applicable to relatively large burner bowls as it provides for admitting air to the central portion thereof to augment that entering adjacent the periphery of the bowl. This insures adequate and properly distributed air for effecting a combustible mixture throughout the whole interior of the bowl. Applying air to the center of the bowl aids combustion and permits more oil to be consumed at high fire, and a correspondingly lesser amount of oil to be burned cleaner at low fire.

Broadly, there is nothing new in admitting air to a burner through a central air distributor. The novelty of our invention resides, first, in obtaining the central air supply from a source remote from that of the peripheral air supply, and in conducting it out of contact with the oil in the burner bowl; and, secondly, in attaching the air admitting means, which preferably consists of an air tube and distributing head, to the closure for the lighting and clean-out opening. Among the advantages arising from these novel features are: the avoidance of any interference with the peripheral air supply, such as would rob certain parts of the vaporous body within the bowl of its proper proportion of air and by so doing cause a smoky flame; the avoidance of chilling, and thus retarding vaporization of the oil within the bowl; the ready removability of the air admitting means or distributor head for the purpose of cleaning it; the removability of the same to facilitate cleaning of the burner bowl; the ability to quickly and easily replace the air admitting means or distributor head in case it becomes burned out, and the ability to conveniently and economically apply the invention to apparatus of the aforesaid class that is in use and which was not originally equipped with the improvement.

Other advantages will appear as we proceed to describe in detail the embodiment of our invention illustrated in the accompanying drawings wherein Fig. 1 is a central vertical section through the lower portion of a warm air furnace equipped with the invention; Fig. 2 is a section on the line 2—2 of Fig. 1; Fig. 3 is a central lon-

gitudinal section through the air tube and distributor head applied to the closure for the lighting and clean-out opening of the burner bowl, and Fig. 4 is a right hand end view of the unit shown in Fig. 3.

Supported within a sheet metal shell 1, on angle iron frames 2, through the medium of brackets 3, is a drum-like combustion chamber 4 having an annular bottom wall 5. Secured, as by bolts 6, to the underside of the wall 5 is the peripheral portion of an annulus 7 whose inner edge is turned downwardly to form a lip 8 that is arranged in spaced relation to a lip 9 that surrounds the inner edge of the annular top wall 10 of a burner bowl 11, the wall 10 being connected to and spaced from the annulus 7 by fastening means or rivets 12. The body of the burner bowl 11 is preferably drawn from relatively heavy sheet metal and includes a bottom wall 13 that is formed with a sump to which fuel is supplied through a pipe 14. By suitable means (not shown)—as, for example, a constant level supply means—the fuel level is maintained below the plane of the marginal portion of said bottom wall. Projecting forwardly from the peripheral wall of the burner bowl 11 is a neck 15 that surrounds the lighting and clean-out opening to which the numeral 16 generally refers.

Enclosing, and spaced radially from, the burner bowl 11 is a housing 19 consisting of a cylindrical wall 20, an annular top wall 21, and a circular bottom wall 22, the former having its inner edge fastened to the underside of the annulus 7, and the latter having a central opening 23 over which a deflector 24 is supported by brackets 25. Air is admitted to the interior of the housing 20 through an air duct 26 having a branch 27 that registers with the opening 23; and the admission of air to said duct may be controlled by a damper 28 that is located adjacent the forward end of the duct 26 where the latter projects through the front of the shell 1 and is shown as covered by a perforated shield 29. The air admitted through the duct 26 finds its way to the interior of the burner bowl 11 through perforations 30 in the peripheral wall thereof and through the space 31 between the annulus 7 and the top wall 10 of the bowl, the air entering through said space being deflected downwardly into the bowl as it escapes through the annular slot defined by the lips 8 and 9. The neck 15 extends through an opening in the cylindrical wall 20 into the interior of a funnel-like structure 32 that opens at its larger end through the front of the shell 1 and has its smaller end engaged with the wall 20 about the neck 15.

The closure for the lighting and clean-out opening 16 is designated 35 and, in the form shown, consists of a relatively deep cup-like member or plug that is drawn from sheet metal and comprises a cylindrical body portion 36, an end wall 37 and a flange 38 that surrounds the outer end of the body portion. A handle 39 is suitably connected to the outer end of the plug or closure 35 to facilitate the insertion of the same within the neck 15 and its withdrawal therefrom. The plug or closure is adapted to be secured within said neck by means consisting of a button 40 on the interior of the neck that engages within an L-shaped slot 41 in the cylindrical wall 36 of the body portion of the plug or closure. Thus a bayonet joint connection is effected between the closure and neck, and the transverse branch of said slot, being inclined to the longitudinal axis of the closure or plug in an appropriate direction, causes the closure or plug to be urged inwardly as it assumes normal position within the neck. This is especially advantageous when a gasket, such as that indicated at 43 in the enlarged views of Figs. 3 and 4, is used between the flange 38 and the end 25 of the neck. The gasket is of suitable packing material and may be held in place by one or more projections 44. While we have shown but one button 40 and slot 41, obviously the number may be increased as desired.

Suitably secured, as by rivets 45, to the end wall 37 of the plug or closure 35, in register with an opening 46 therein, is the base flange 47 of an air tube 48 that has its inner end turned upwardly and flared to provide a flange 49. The unit comprising the plug or closure 35 and the air tube 48 is of a length that causes the inner end of said tube to be located at about the center of the bowl 11 when the plug or closure 35 is in place. A distributor head 50, preferably formed of sheet metal, is attached to the flange 49 by having its rim curled about the edge of the flange, and the peripheral wall of said head is provided with perforations 52. It will be observed especially from Fig. 4 that the tube 48 is so located with respect to the longitudinal axis of the plug or closure 35 that the distributor head 50 is practically within the diameter of the closure or plug. Further, it will be observed that the head is located inwardly of the inner end of the plug or closure a distance substantially equal to the length of the latter. By reason of these facts, the head may be readily projected through the neck and brought into position within the burner bowl as the plug or closure is inserted within the neck.

In the operation of the apparatus air additional to that admitted through the openings 30 and the space 31 is drawn in through the hollow body of the plug or closure 35 and through the air tube 48 and is projected radially within the burner bowl 60 through the perforations 52 of the distributor head 50. By obtaining the central air supply from a point outside the housing 19, there is no likelihood of depriving the openings 30 and the space 31 of their air requirements for maintaining a properly balanced condition inside the burner bowl; and by bringing the air admitting tube 48 inwardly from one side above the bottom of the bowl, in contradistinction to bringing it up through the bottom in accordance with the usual practice, there will be no danger of the temperature of the fresh air chilling the oil in the bowl and thus retarding its vaporization. Furthermore, this arrangement insures greater heating 75 of the incoming air before it is finally discharged

into the burner which contributes to a more effective gasification of the fuel.

When it is desired to light the burner, the handle 39 is grasped and the plug or closure turned to bring the longitudinal branch of the slot 41 in line with the button 40 and the unit comprising said closure and the air tube is withdrawn from the neck 15. Oil admitted through the pipe 14 to the sump in the bottom of the bowl 11 may now be ignited by placing a lighted match, taper, a piece of burning paper or other suitable material within the burner bowl through the opening 16, after which the closure 35 may be replaced. The charred match, paper or other material by which the oil was lighted may be left in the burner bowl, as its presence will not adversely affect the operation of the burner, and when such an amount of this charred material and carbon have accumulated within the bowl as makes their removal desirable, the same may be cleaned out through the opening 16.

Having thus described our invention, what we claim is:

1. In combustion apparatus, a burner bowl, a housing enclosing and spaced from the bowl and having an air admitting opening, the bowl being provided with means for admitting air adjacent its periphery from the space between the housing and bowl, air conducting means extending from a point outside the housing into the bowl from one side and above the bottom thereof and terminating approximately centrally of the bowl, and means for delivering fuel to the bowl.

2. In combustion apparatus, a burner bowl having an opening in its wall through which access is had to its interior, a closure for said opening, means on the closure for carrying air into the interior portion of the bowl in spaced relation to its peripheral wall, and further means for delivering fuel to the bowl.

3. In combustion apparatus, a burner bowl having an opening in its wall through which access is had to its interior, a closure for said opening, means carried by the closure for conducting air to the internal region of the bowl and spreading it toward the peripheral wall thereof, and further means for delivering fuel to the bowl.

4. In combustion apparatus, a burner bowl having an opening in its wall through which access is had to its interior, a closure for said opening, means carried by the closure for admitting air to the bowl substantially centrally thereof, and means for delivering fuel to the bowl.

5. In combustion apparatus, a burner bowl having an opening in its wall through which access is had to its interior, a closure for said opening, means carried by the closure for admitting air to the bowl and distributing it substantially centrally thereof, and means for delivering fuel to the bowl.

6. In combustion apparatus, a burner bowl having an opening in its wall through which access is had to its interior, a closure for said opening, an air tube carried by said closure and projecting into the bowl, and means for delivering fuel to the bowl.

7. In combustion apparatus, a burner bowl having an opening in its wall through which access is had to its interior, a closure for said opening, an air tube carried by said closure and projecting into the bowl, a distributing head on the inner end of said tube, and means for delivering fuel to the bowl.

8. In combustion apparatus, a burner bowl having an opening in its side wall, a removable

closure for said opening, an air tube carried by said closure and projecting into the bowl and terminating approximately centrally thereof, and means for delivering fuel to the bowl.

5. 9. In combustion apparatus, a burner bowl having an opening in its wall through which access is had to its interior, a closure for said opening, an air tube carried by said closure and projecting into the bowl, an air distributor on the 10 inner end of the tube and situated approximately centrally of the bowl, and means for delivering fuel to the bowl.

10. 10. In combustion apparatus, a burner bowl having an opening in its wall through which access is had to its interior, a closure for said opening, an air tube carried by said closure and projecting into the bowl, a perforated distributor head on the inner end of the tube for projecting air toward the peripheral wall of the bowl, and 15 means for delivering fuel oil to the bowl.

11. 11. In combustion apparatus, a burner bowl having an opening in its side wall through which access is had to its interior, a neck surrounding said opening, a plug for closing said opening, an air distributor projecting from the inner end of the 20 plug and having, with the plug, an air admitting passageway, and means for delivering fuel to the bowl.

12. 12. In combustion apparatus, a burner bowl having an opening in its side wall through which access is had to its interior, a neck surrounding said opening, a plug for closing said opening, an air distributor projecting from the inner end of the 25 plug and having, with the plug, an air admitting passageway, means for delivering fuel to the bowl, and means for sealing the joint between the plug and neck.

13. 13. In combustion apparatus, a burner bowl having an opening in its side wall through which access is had to its interior, a neck surrounding said opening, a hollow plug for closing said opening, an air distributor carried by the inner end of the 30 plug and communicating with the interior thereof, and means for delivering fuel to the burner bowl.

14. 14. In combustion apparatus, a burner bowl having an opening in its side wall through which access is had to its interior, a neck surrounding said opening, a hollow plug for closing said opening and having a bayonet joint connection with 35

said neck, a handle on the outer end of the plug, an air distributor carried by the inner end of the plug and communicating with the interior thereof, and means for delivering fuel to the burner bowl.

15. 15. In combustion apparatus, a burner bowl having an opening in its side wall through which access may be had to the interior thereof for lighting and cleaning purposes, a neck surrounding said opening and projecting forwardly from 10 the bowl, a hollow plug for closing said opening having a wall at its inner end, an air tube carried by the end wall of the plug and projecting inwardly therefrom, said end wall having an opening 15 registering with the bore of the tube, a distributor head on the inner end of the tube, said head and tube being substantially within the diameter of the plug, and means for delivering fuel oil to the burner bowl.

16. 16. In combustion apparatus, a burner bowl 20 having an opening in its side wall through which access may be had to the interior thereof for lighting and cleaning purposes, a neck surrounding said opening and projecting forwardly from the bowl, a hollow plug for closing said opening 25 having a wall at its inner end and a flange at its outer end arranged in opposed relation to the corresponding end of the neck, a gasket interposed between said flange and neck, an air tube carried by the end wall of the plug and projecting inwardly therefrom and offset laterally from the longitudinal axis of the plug, the end wall having an opening registering with the bore of the tube, the inner end of the tube being formed with an elbow and having applied thereto a distributor 30 head, said head being substantially within the diameter of the plug, and means for delivering fuel oil to the burner bowl.

17. 17. In combustion apparatus, a burner bowl, a housing enclosing and spaced from the bowl and 40 having an air admitting opening, the bowl being provided with means for admitting air adjacent its periphery from the space between the housing and bowl, air conducting means extending from a point outside the housing into the bowl and 45 terminating approximately centrally thereof, and means for delivering fuel to the bowl.
